UNITED STATES PATENT OFFICE

LOUIS PORCHOFF, OF FLUSHING, NEW YORK.

WASHING APPARATUS.

1,251,567.

Specification of Letters Patent Patented Jan. 1, 1913.

Application filed November 14, 1912. Serial No. 131,851.

To all whom it may concern:

Be it known that I, Louis Porchoff, a citizen of the United States, residing at Flushing, in the county of Queens and State of New York, have invented certain new and useful Improvements in Tumbling Apparatus, of which the following is a full, clear, and exact specification.

This invention relates to apparatus for carrying masses of material through successive fluids, and more particularly has for its object the production of apparatus for carrying material through a series of containers and wherein the entire handling of the material shall be accomplished mechanically.

A further object of the invention is to provide simple apparatus which will carry a continuous stream of small articles such as nails, cartridge shells, etc., through successive containers and at the same time constantly tumble or agitate the material to bring all parts of it into contact with the fluids in the containers.

It is also an object of this invention to so construct the carrying means that the rate of progress of the material through all the containers as a whole may be easily varied while the length of time that the material remains in each container is capable of separate adjustment. In this way the apparatus is made readily changeable to meet the requirements of different articles and different processes without troublesome reconstruction and by simple adjustments of the parts.

In the accompanying drawings,

Figure 1 is a plan view of washing and drying apparatus embodying this invention;

Fig. 2 is an elevation of the same partly in section;

Fig. 3 is a partial view of the receiving end of the apparatus;

Fig. 4 is a similar view of the discharging end;

Fig. 5 is a face view of one of the scoops or shovels, and

Fig. 6 is a partial end view of the same.

In the washing and drying apparatus shown, A, B, C and D are tanks containing washing fluids in proper sequence, such as a pickling bath, water, a soap solution, and water again. After the final water rinsing in tank D there is provided a heating and drying compartment E. The articles are washed by being dipped into each tank in succession and are finally dried in compartment

E from which they are automatically discharged.

To carry the articles through the successive washing and drying means a series of 60 rotary tumbling barrels or drums 1, 2, 3, 4 and 5 are provided for carrying the articles. Between the drums buckets 35 and cylinders 23 are provided to pass the articles from each drum to the next succeeding one. The 65 drums, buckets and cylinders are supported together and the general rate of progression of the material is controlled by mounting this structure to incline downward toward the delivery end of the machine. In 70 this way gravity and the rotation of the apparatus combine to feed the articles through the successive steps of the process. To provide for this general inclination of the parts the entire rotary structure is 75 mounted upon a pivoted frame comprising side members 8 swiveled at 9 to standards 10 at the receiving end and joined by cross bar 11 at the discharge. The bars 8 beyond the bar 11 have extended ends adjustable 80 in guides 12 of rear standards 13 by supporting screws 14. By turning screws 14 the angle of inclination of the apparatus can be adjusted to control the rate of progress of the material being treated.

Each of the tumbling barrels or drums 1, 2, 3, 4 and 5 comprises opposite heads 16 and 17 surrounded by a peripheral band of fabric or perforated material 18 and held together by the outer rods 19 and the 90 inner bars 50 for stirring the material. These heads 16 and 17 are mounted upon a central shaft 20 by hubs 21 connected to the outer solid portions of the heads by spokes 22. The drums are suitably spaced apart 95 and are connected by cylinders 23 supported by the heads 16, 17 to form passages between the drums. The middle drum and end drums are provided with bearing rings 24 supported on rollers 25 in cradles 26 lying 100 on the side beams 8 of the frame. The cross piece 11 of the frame carries a bearing 27 for the central shaft 20 provided with a collar 21 engaging said bearing to hold the shaft against end thrust.

The drums and their associated structures are therefore rotatable together as a unit in the supports provided by the frame. To rotate these parts a shaft 30 driven in any suitable manner is supported in bearings 31 on a side member 8 and carries a pinion 32 engaging a large gear 33 formed

on the periphery of the head 17 of the middle drum 3.

At the entrance end of the machine there is provided a receiving bucket 50 pivoted at 51 to the front standards 10 and positioned when in lowered position within the tank 53. This receiving bucket is made preferably of perforated boiler plate material and is provided with a strap 54 by which it is 10 raised to dump the material within it into the entrance cylinder 55 attached to the front head 16 of tumbling barrel 1.

In order to feed the material from each drum into the next succeeding drum, transfer buckets 35 are carried by each head 17. These buckets are in the shape of hollow cones attached to the heads by their bases which are just large enough to span the spokes 22 and guide the material into the 20 cylinders 23. For about one quarter of a circle each bucket is cut away to provide an opening to receive the articles scooped up by the shovel 36 extending from one side of the cut out portion of the bucket. The 25 shovel comprises a fixed plate 37 and a movable angle blade 38 carried by bracket piece 39 having lugs 40. The lugs 40 extend behind the plate 37 and carry rods 41 and 42 sliding in guides 43 and 44 projecting from plate 37. Rod 41 extends through head 17 of the drum and carries gage marks to indicate the setting of the blade. Rod 42 also extends through head 17 and is screw threaded to carry adjusting thumb nut 45 30 swiveled in plate 46. Turning of this nut adjusts the shovel blade to vary the width of the shovel and consequently control the amount of material carried up by the shovel and discharged into the bucket. The outer 40 end of the shovel is carried into close proximity with the drum periphery so that at each rotation it receives a part of the material at the bottom of the drum and carries it up and discharges it into the transfer 45 bucket which guides the articles into the cylinder 23 through which it passes to the next drum. In this manner the material is carried through all of the drums and is finally discharged through outlet 47 of the 50 drying drum into a chute or waiting containers.

The general inclination of the apparatus provides means for moving the material through the drums and their connecting cylinders and the adjustment of the inclination affords means whereby the feed can be varied to suit the character of the articles or the process which they are undergoing. The adjustment of the bucket blades not only 55 determines the area in contact with the material, but also varies the point in the travel of the material at which these shovels become effective as each of these shovels is adjustable the length of time that the material 60 remains in any drum can be independently

varied to suitably prolong or shorten the period of action at a given drum. This makes each unit of the apparatus independently adjustable to meet the varying conditions of different articles and processes. All 70 the adjustments of the machine are easily performed without removal of parts or in any wise reconstructing the machine. The entire progression mechanism is in the form of a single integral member which does not 75 depend upon the relative movement of any parts in its operation. The apparatus is simple and durable in form.

It is evident that the various parts of the mechanism may be formed of suitable material. The drum heads 16 and 17 are formed preferably of aluminum, while their peripheral bands are formed preferably of some non-absorbent material. It is apparent that other means than those shown may 80 be used to effect the desired adjustments of the parts.

The apparatus herein described is especially useful in the economical manufacture of cartridge shells, which as is well known, 90 are made from sheet metal by a series of cupping or drawing operations. In the case of brass shells, such as for military rifle cartridges, between each drawing or pressing operation the shell must be annealed, 95 and in the manufacture of a single shell there may be six or eight annealing operations. Each time a shell is annealed, it has to be pickled to remove the scale, then washed to remove the acid or pickling fluid, 100 then passed into a soap or other weak alkali solution to neutralize any residue acid, then again washed to remove the soap, and finally dried before the next drawing or punching operation. The present invention is especially adapted for economically handling 105 large quantities of material of this character, it being seen that the entire handling of the material is automatic and it is insured that absolutely clean pieces will be 110 delivered by this machine for the subsequent punching, pressing, dieing, or other operation.

The invention is not confined to the specific embodiment shown and described, but 115 is intended to cover such modifications thereof as fall within the scope of the appended claims.

Having thus described my invention, I declare that what I claim as new and desire 120 to secure by Letters Patent, is:—

1. In tumbling apparatus for treating material by passing it through a series of tanks, the combination with a unitary rotary member comprising a plurality of drums 125 connected so as to form a single container adapted to tumble the material in each tank and carry it through the tanks in succession, of means for supporting said member in tilted position to incline the axes of said 130

drums so that the material will be fed therethrough by gravity, and means for adjusting said supporting means to vary the rate of progress of the material and the tumbling effect irrespective of the speed of rotation of the drums.

2. In tumbling apparatus for treating material by passing it through a series of tanks, the combination with a unitary rotary member comprising a plurality of connected drums adapted to tumble the material in each tank, of transfer means between the drums and rotating therewith for moving the material from one drum to the next so that the material is carried through the tanks in succession, means for supporting said member in tilted position to incline the axes of said drums so that the material will be fed therethrough by gravity, means for adjusting said supporting means to vary the rate of progress of the material and the tumbling effect irrespective of the speed of rotation of the drums, and means for adjusting said transfer means between certain of said drums to independently control the length of time the material remains in the corresponding drum.

3. In apparatus for carrying material through a tank, the combination with a rotary drum mounted to support the material in said tank, of means operated by the rotation of said drum for lifting material out of the tank comprising an axial conical chamber supported by one head of said drum and adapted to discharge material therefrom, and a scoop blade leading directly into said chamber and rotating with said drum to lift material from said drum into said chamber.

4. In apparatus for transferring material through a series of tanks, the combination with a rotary member comprising a series of open ended drums adapted to dip into said tanks and permeable by the liquid therein, of axial cylindrical passages connecting the open ends of said drums and rotating therewith, and means for lifting the material out of each drum and discharging it into the next connecting passage comprising an axial conical chamber opening into the receiving end of the corresponding passage and a scoop blade for lifting the material into said chamber.

5. The combination with a plurality of tanks, of a unitary rotary member for transferring material through said tanks in succession comprising a rotatable shaft member, a plurality of open ended drum contain-

ers spaced along said shaft and rigid therewith, connecting cylinders between successive drums, compartments in said drums opening into said cylinders and coaxial therewith, and scoop blades connected to said compartments for lifting material thereinto by the rotation of said unitary member.

6. The combination with a plurality of tanks, of a unitary rotary member for transferring articles through said tanks in succession comprising a shaft, a plurality of drums on said shaft formed by a series of open drum heads connected directly to said shaft and having peripheral sheets supporting the articles in said tanks, a cylinder connecting the openings in the heads of adjacent drums for passing the articles from one drum to the next, and scoop members for lifting material out of said tanks into each connecting cylinder by the rotation of said unitary member.

7. In tumbling apparatus adapted to treat material by passing it through a plurality of tanks, the combination with a unitary rotary series of independent chambers comprising a plurality of open headed tumbler drums comprising permeable material adapted to dip into the tanks and support the material to be treated therein, cylinders connecting the openings in the heads of said drums and bridging the ends of said tanks, and means for transferring material from one drum into the next cylinder rotating with said drum and comprising means controlling the transfer of material from said drum to said cylinder so that the length of time the material remains in said drum may be varied.

8. In tumbling apparatus for treating material by passing it through a series of tanks, the combination with a rotary member comprising a central shaft, a series of open drum heads fastened to said shaft, peripheral sheets of permeable material on said heads forming a series of drums dipping into said tanks, and an intermediate transfer cylinder between adjacent drum heads and of less diameter than said drums, of means for rotatably supporting said member in tilted position to incline the axes of said drums and cylinder comprising inclined side beams and cross pieces between said beams having a cradle bearing, and a bearing track supported by one of said drum heads and rotating on said bearing.

In testimony whereof I affix my signature.

LOUIS POTTHOFF.
